UNITED STATES PATENT OFFICE.

FREDERICK W. LETSCH, OF BALTIMORE, MARYLAND.

TYPOGRAPHIC MACHINE.

1,392,017.

Specification of Letters Patent. Patented Sept. 27, 1921.

Application filed July 18, 1916, Serial No. 109,955. Renewed December 28, 1920. Serial No. 433,740.

To all whom it may concern:

Be it known that I, FREDERICK W. LETSCH, a citizen of the United States, and a resident of the city of Baltimore, State of Maryland, 5 have invented certain new and useful Improvements in Typographic Machines, of which the following is a specification.

This invention relates to typographic machines and particularly to a machine of the 10 type illustrated and described in my pending application Serial No. 99,201 filed May 22, 1916. In the said machine there are a limited number of matrix bars each containing 15 a full assortment of the characters required in the work for which the machine is adapted. A keyboard is operated, as is usual in typographic machines, and the immediate effect of such operation is to move forward pins in a plate corresponding to the 20 respective characters of the keys operated. The pin plate is then moved under the matrix bars and the matrix bars are lowered until they are brought to rest by their respective projected pins, thus bringing into 25 line characters on the several matrix bars to form the word, number, or other group of characters desired. The matrices are then clamped against a mold and a logotype is cast, after which the matrices are distributed by raising the matrix bars to their 30 normal position and the operation may be repeated.

The present invention relates more particularly to an automatic means for adjusting 35 the mold to correspond to the number of characters in the logotype. In the particular style of machine referred to the matrix bars are of uniform thickness throughout and the matrices have faces of 40 substantially uniform width so that the type on the logotypes are equally spaced from center to center. This equality in the matrix faces admits of the automatic adjustment of the width of the mold in the manner about 45 to be described.

Referring to the accompanying drawings, Figure 1 is a front elevation of portion 50 of a logotype machine embodying the invention;

Fig. 2 is a plan partly in section on the line 2—2 of Fig. 1;

Fig. 3 is a side elevation of the portion of the machine shown in Fig. 1, parts being broken away;

Fig. 4 is a section on the line 4—4 of Fig. 1;

Fig. 5 is a section on the line 5—5 of Fig. 3;

Fig. 6 illustrates the scale for setting the gage block; and

Fig. 7 is a section on the line 7—7 of Fig. 6.

The machine is provided with a suitable key-board K, a mold M and matrix bars B. The mold comprises upper and lower sections 20, 21, an end gate 22, and a body piece 23. During the casting operation the end gate closes the left end of the mold (Fig. 1) and the body piece closes the right end of the mold, the body piece being adjustable 65 to vary the width of the mold opening and also being movable through the mold to eject the logotype when the end gate is raised, after the casting operation.

The present invention comprises means 75 for automatically setting the body piece in accordance with the width of the logotype to be cast. This is accomplished by the following mechanism. A space key 24 is carried by a rocking lever 25 and the keys 26 80 of the key-board overlie the space key so that it acts as a "universal bar" causing the lever 25 to be rocked when any key is operated. The rear end of lever 25 is connected with a lever 27 pivoted at 28 and the rear end 85 of lever 27 is connected by a link 29 with a lever 30 (Fig. 2). The lever 27 is normally held in the position shown in Fig. 3 by a spring 31 which thus holds the universal bar or space key 24 in its elevated position. 90 The lever 30 is pivoted to a bracket at 32 and its right end engages an opening 33 in a vertically sliding block 34. Pivoted on the block 34 is a moving pawl 35 and above it on a fixed pivot is a holding pawl 36, both being spring pressed normally into engagement with a vertically sliding ratchet bar 37 provided with ratchet teeth on its forward edge. As shown in Figs. 3 and 5, the ratchet bar 37 has perforated lugs 100 38 through which slides a rod 39. Upon the rod 39 is a fixed collar 40 which is normally held against the upper lug 38 by means of a coiled spring 41, said spring encircling the rod and having its lower 105 end supported on the lower lug 38.

Supported on the rod 39 is a vertically sliding stepped gage block 44, each step of which equals in depth, horizontally, the thickness of a matrix bar. The steps of the 110 gage block act as stops for the slide 45 which moves the body piece 23, the slide 45 being

provided with an abutment 46 adapted to contact with the respective steps of the block 44. The slide 45 is moved to the left after each casting operation to cause the body piece to eject the cast slug from the mold. During this operation the stepped gage block 44 is adjusted vertically to bring the proper step opposite the abutment 46 to regulate the width of the mold for the next logotype and when the slide 44 is returned to its right hand position the abutment 46 contacts with the selected step of the gage and the parts remain in this position until the next logotype is cast. The slide 45 may be operated in any suitable manner. As shown, it is moved by an arm 47 operated periodically by a cam or other suitable means.

The operation of setting the stepped gage block is as follows: As the keys corresponding to the letters of a given logotype are successively depressed, the pawl 35 is moved up and down, raising the ratchet bar 37 step by step, the bar being prevented from receding by the holding pawl 36. During this time the stepped block 44 may be in an elevated position and retained by the abutment 46. If the rod 39 engages the gage block while it is locked, the rod will remain stationary while the ratchet bar 37 may continue to rise. Upon the release of the gage block the spring 41 will carry the rod 39 and the gage block to the position determined by the elevation of the ratchet bar and the abutment 46 will then move into engagement with the gage block and hold the body piece in position to cast the next logotype. If the rod 39 does not extend up to the gage block when the latter is released, it will drop by gravity onto the rod 39 and thus be positioned for the succeeding line. It thus follows that when the keys have been operated for a given logotype the step block will be adjusted until the step corresponding to the width of the proposed logotype is opposite the abutment or projection 46 and the body piece will be adjusted accordingly.

During the casting operation the pawls 35, 36 are withdrawn from the ratchet bar 37 permitting the bar to drop to its lowest position as shown in Fig. 3.

The operation of the key-board to produce the next logotype may then proceed immediately, while the previously indicated logotype is being cast. The pawls are withdrawn from the ratchet by means of a sliding bar 48 (Figs. 1 and 2) which has a cam 49 on its right end adapted to coöperate with a roller 50 pivotally mounted in a yoke 51 which is connected with or is a part of the pawl 36. The lower end of pawl 36 engages a finger 52 on the moving pawl 35 and the pawls are thus simultaneously withdrawn from the ratchet bar.

The sliding bar 48 is operated automatically as follows:—The matrix bars B are raised after each casting operation to their normal or inoperative positions by engagement with a matrix frame 53 which slides vertically in the fixed frame of the machine. The engagement of the matrix bars with the frame 53 is not disclosed in the drawing but it will be understood that each time frame 53 rises the bars are raised and the parts remain in the raised position until the bars are to be dropped and rearranged for a succeeding logotype. On the frame 53 (Figs. 1 and 2) is a projection 54 which engages the horizontal arm of an elbow lever 55 when the matrix frame is lowered. The vertical arm of this lever 55 engages pins on the sliding bar 48 and the bar is moved to the right each time that the matrix frame is moved down, thus withdrawing the pawls 35, 36, and permitting the ratchet bar 37 to drop. The elbow lever 55 is preferably provided with a roller 56 to contact with the projection 54.

My invention is particularly designed to operate in conjunction with the various parts of the machine described in my pending application above referred to. In said application there are two pin-plates, one of which is controlling the assembling of the matrix bars while the other is being manipulated to control the matrix bars of the succeeding logotype. In said machine the present invention operates as follows: During the casting of one logotype the stepped block 44 is held from dropping by the abutment 46 and at the same time the ratchet 37 is being raised to readjust the stepped block by the manipulation of the keys for the succeeding logotype. After a logotype is cast the matrix bars are raised and then lowered. In this interval the stepped block is released.

It is sometimes desirable to cast duplicate logotypes, that is, to make two or more castings from the same assemblage of matrices. To accomplish this, means (not shown) are provided for preventing distribution of the matrices, or returning the matrices to the same position after the first logotype is cast. Means are also provided for preventing movement of the gage block while a series of duplicate logotypes are being cast. As shown in the drawing, these means comprise a rod 60, the lower end of which is connected to the ratchet bar 37 while the upper end is provided with a clamping device to hold it in any fixed relation to the stationary frame 61 in which it is mounted. As shown in Figs. 3, 6 and 7, the rod 60 slides vertically in a slot or recess and at its upper end it is provided with a thumb screw 62 which clamps the plate 63 on the face of the frame of the machine and clamps the rod 60 in any desired position. The plate 63 is provided with an index mark 64 and

the column or frame in which the part 60 slides is provided with graduations 65 which coöperate with the index 64 to provide for accurate adjustment of the gage block. The 5 numbers on the scale 65 may index the respective numbers of characters in logotypes of different lengths.

It will be understood that all of the operations of the machine under normal circumstances are automatic excepting the operation of the keys and of the usual starting lever with which such machines are provided.

Having described the invention what is claimed is:—

15 1. In a typographic machine, the combination with a mold and a plurality of matrices, of means for assembling selected matrices in groups to register with the mold for casting logotypes, a keyboard, a body piece, 20 and means controlled by the keyboard for adjusting the body piece automatically to position to regulate the body widths of the respective logotypes.

25 2. In a typographic machine, the combination with a mold having a body piece movable to adjust the mold opening, of matrices, a keyboard for selecting matrices, means for assembling matrices in groups, to 30 coöperate with the mold, and means controlled by the keyboard for adjusting the body piece in accordance with the groups of matrices selected.

35 3. In a typographic machine, the combination with a mold having an adjustable body piece, of a keyboard, a series of matrix bars of uniform width, means controlled by the operation of the keyboard for assembling matrices in groups, and means operated from the keyboard for adjusting the 40 body piece in accordance with the number of matrix bars selected.

45 4. In a typographic machine, the combination with a mold and a plurality of matrices, of means for assembling matrices in selected groups to register with the mold for casting logotypes, a keyboard, a body piece, means controlled by the keyboard for adjusting the body piece automatically to position to regulate the body widths of the respective 50 logotypes, and manually operated means for holding the body piece in any position to which it has been adjusted, for the purpose described.

55 5. In a typographic machine, the combination with a mold having an adjustable

body piece, of a keyboard, and means for adjusting the body piece from the keyboard comprising a universal bar, a stepped block, a ratchet and pawl device for adjusting said block, and means for causing the block to 60 act as a gage for the body piece.

6. In a typographic machine, the combination with a mold having a body piece and matrices to coöperate with the mold, of a keyboard, a stepped gage block, means for 65 adjusting the block in accordance with the number of keys operated to compose a given line of characters, the body piece being adjusted by contact with said block.

7. In a typographic machine, the combination with a mold having a body piece, a plurality of matrices and a key-board, of means for adjusting the body piece according to the operation of the key-board comprising a ratchet bar, a gage block, and a 75 yielding member carried by the ratchet bar and operating upon the gage block.

8. In a typographic machine, the combination with a mold having a body piece, and matrices to coöperate with the mold, of a 80 gage block for adjusting the mold automatically after each operation, and means for setting said gage block for the respective lines of type to be cast comprising a ratchet bar, and a rod yieldingly supported by the 85 ratchet bar and adapted to support the gage block.

9. In a typographic machine, the combination with a mold having a body piece, and matrices to coöperate with the mold, of a 90 gage block for adjusting the mold automatically after each operation, and means for setting said gage block for the respective lines of type to be cast comprising a ratchet bar, and a rod yieldingly supported by the 95 ratchet bar and adapted to support the gage block, said rod being adapted to slide in guides attached to the ratchet bar.

10. In a typographic machine, the combination with a mold and a body piece of a 100 stepped gage block for limiting the adjustment of the body piece, a rod supporting said gage block but disconnected therefrom, a ratchet bar, a spring supporting the rod yieldably on the ratchet bar, a key-board and 105 connections from the key-board for operating said ratchet bar.

In testimony whereof I affix my signature.

FREDERICK W. LETSCH.
